UNITED STATES PATENT OFFICE.

ERIK HERMAN ODERMAN, OF WAYNESBORO, PENNSYLVANIA, ASSIGNOR TO FRICK COMPANY, OF WAYNESBORO, PENNSYLVANIA, A CORPORATION.

DESIGN FOR A MACHINE-FRAME.

42,294.

Specification for Design.

Patented Mar. 12, 1912.

Application filed February 6, 1909. Serial No. 476,572. Term of patent 14 years.

To all whom it may concern:

Be it known that I, ERIK HERMAN ODERMAN, a citizen of the United States, residing at Waynesboro, in the county of Franklin and State of Pennsylvania, have invented a new, original, and ornamental Design for Machine-Frames, of which the following is a specification.

My said design consists in an ornamental form of a machine frame, especially designed for ice making machines.

In the drawings, Figure 1 shows said machine frame in top plan, Fig. 2 in elevation as seen when looking in the direction indicated by the arrows on the dotted line 2—2

in Fig. 1, and Fig. 3 in elevation when seen in the direction indicated by the arrows 3—3 in Fig. 1.

What I claim is:

The ornamental design for a machine frame, substantially as shown.

In witness whereof, I have hereunto set my hand and seal at Waynesboro, Pennsylvania this fourth day of February, A. D. nineteen hundred and nine.

ERIK HERMAN ODERMAN. [L. S.]
